UNITED STATES PATENT OFFICE.

FREDERICK CRAIB, OF MARTINEZ, CALIFORNIA.

DESIGN FOR AN ELECTRIC-LIGHT FIXTURE.

Application filed May 2, 1925. Serial No. 13,309. Term of patent 3½ years.

To all whom it may concern:

Be it known that I, FREDERICK CRAIB, a citizen of the United States, residing in Martinez, in the county of Contra Costa and State of California, have invented a new, original, and ornamental Design for Electric-Light Fixtures, of which the following is a specification, reference being had to accompanying drawing, forming part thereof, wherein—

Fig. 1 is a bottom plan view illustrating one-half of a fixture embodying my design, and

Fig. 2 is a side elevation.

I claim:

The ornamental design for an electric light fixture as shown.

FREDERICK CRAIB.
